UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,841, dated October 24, 1893.

Application filed September 19, 1893. Serial No. 485,906. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of fleur-de-lis ornaments placed at equal distances apart over the surface of the paper with smaller similarly shaped ornaments arranged in vertical rows between the fleur-de-lis ornaments as represented in the accompanying drawing. The fleur-de-lis ornaments are also arranged in groups and connected by ornamental scrolls

as represented in the upper portion of the accompanying drawing forming the border portion of said design.

What I claim is—

1. The design for a wall paper herein shown and described.
2. In the design for a wall paper the border herein shown and described.

Witness my hand this 15th day of September, 1893.

CHARLES BOOZE.
